US0D1045917S

(12) United States Design Patent (10) Patent No.: US D1,045,917 S
(45) Date of Patent:  Oct. 8, 2024

(54) DISPLAY SCREEN OR PORTION THEREOF WITH GRAPHICAL USER INTERFACE

(71) Applicant: Mitsubishi Electric Corporation, Tokyo (JP)

(72) Inventors: Hitoshi Yoshizawa, Tokyo (JP); Tsutomu Matsubara, Tokyo (JP); Masato Hirai, Tokyo (JP); Takashi Yamauchi, Tokyo (JP)

(73) Assignee: Mitsubishi Electric Corporation, Tokyo (JP)

() Term: 15 Years

(21) Appl. No.: 29/806,606

(22) Filed: Sep. 3, 2021

(30) Foreign Application Priority Data

Mar. 11, 2021 (JP) ..... 2021-004986 D

(51) LOC (14) Cl. 14-04

(52) U.S. Cl.

USPC D14/486

(58) Field of Classification Search

USPC D14/485-95

CPC G06F 3/048; G06F 3/0481; G06F 3/04812; G06F 3/04815; G06F 3/04817; G06F 3/0482; G06F 3/0483; G06F 3/0484; G06F 3/04842; G06F 3/04845; G06F 3/04847; G06F 3/0485; G06F 3/0486; G06F 3/0487; G06F 3/0488; G06F 3/04883; G06F 3/04886; G06F 3/0489; G06F 3/04892; G06F 3/04895; G06F 3/04897
